Thomas M. Southwick, of Troy, New York,
Letter Patent.

The schedule referred to in this Letters Patent and making part of the same, containing a description in the words of the said Thomas M. Southwick, himself of his improvement in a wrought iron stove for burning anthracite coal called Southwick's Pyramidal Stove -

Be it known that I Thomas M. Southwick of Troy Rensselaer County, State of New York, have made an improvement in the useful art, being a wrought iron stove for burning anthracite coal called "Southwick's Pyramidal Stove" which is described as follows: This stove consists of four sections; The first or lower section, is made circular of any convenient size, and is fastened to the base, by screws passing thro' ears at the bottom, and two brads or iron bolts to the under side of the base, and fastened by nuts on the under side. The base is overlaid with brads or iron

This section has a double bottom, and double sides making an air tight vessel, leaving a vacant space for the drawer to receive the ashes. The drawer is faced with brads or iron, the handle of brads or iron and made fast to the drawer with a screw passing through the handle and fastened with a nut inside. A brad or iron rim on the top of this section and a small, sliding door on the back side, into this air tight chamber are introduced three tubes more or less reaching into the second section, for conveying warm air downwards into the close chamber below, by which means the air near the floor is warmed. The second section has two doors one at the bottom and one about two third distance from the bottom to the top, with hinges and locks, the bottom door faced with brads or iron, & the handle made fast to the door by a screw, and nut, the same as the front of the drawer in the

first section, The upper door has a slide bolt, a trap or iron handle, a screw passing through the handle and through the bolt and fastened inside by a nut. There is a space cut in the door sufficient to give play to the bolt, with iron flap in the top of the door and iron flap in the stove on each side of the door on an equal line with the flap, on the top of the door, about half way between the doors are three or more iron knees riveted to the stove inside which support a wrought iron rim round the inside of the stove. This rim supports a cast iron horizontal rim, with a small ring on the rim, on the under side and a perpendicular rim on the upper side leaving a space between the perpendicular rim and the stove for three or more iron tubes to pass down into the vacuum in the first section, The top of the tubes are to be of equal height with the perpendicular rim, In the space inside of the horizontal cast rim is a furnace of soap stone cast with wrought iron, At the bottom of the furnace is an iron drop grate with a hinge and button to hold up the grate, the furnace is confined to the cast iron rim by four screws, passing through the horizontal rim inside of the perpendicular rim & outside of the ring, on the underside of the rim & through the rim of the grate in the underside of the furnace & made fast by nut on the under side of the grate. on the bottom of this section is a lifter of the size of the drawer in the first section. The third section has iron flap in front, a boiler made let in at the top, with a cover, a trap or iron handle, holes in the cover to pass off steam, the bottom ornamented with a trap or iron rim setting off from the stove, The fourth section has a damper, near the top of the boiler in the third section and made fast by trap or iron handle, on the outside of the stove, on the top is a trap or iron ball or iron or one or more rising from the top. the bottom and top ornamented with a trap or iron rim setting off from the stove, about two thirds the distance from the bottom to the top of this section is a

a collar containing a damper, and made fast outside with brass hardware, & on this collar enters the stove pipe -

Operation. The fuel being introduced into the grate or furnace in the second section of the door with charcoal & other materials, proper for kindling and fire applied, the door is shut; draft is given from below, and the anhydrite coal ignited, the heat传导 into the upper section, heating the water in the boilers and also传导 into the close chamber, below by the tube - warming the air in the lower part of the room, which will be very convenient for the feet the dampers being applied according to their several uses. By means of the soap stone lining and construction of the furnace, the boiler containing water, the body of the stove, will never become red hot, thus preventing the oxygen of the air in the room from being destroyed, as is the case with common stoves, on account of its affinity to red hot iron, -

At night the drop grate, is let down by turning a button, & the contents sifted by the lifter, the ashes falling into the drawer below, the cinder separated and the coal remaining put into the grate ^{for} next morning. The invention here claimed and desired to be secured by Letters Patent, consists in the arrangement, and adaptation of the several parts of the stove so as to produce the one described, but I particularly claim the tube which conveys the heated air downward into the close recess below for warming the feet, & the construction of the furnace containing the coal. For a further illustration of my invention I refer to the model and drawing of the same deposited in the Patent Office -
